SEWING MACHINE

Dave Fischbein, Minneapolis, Minn.

Application January 14, 1946, Serial No. 641,091

3 Claims. (Cl. 112—215)

1

My present invention relates to improvements in sewing machines and, more particularly, to the work feed dog thereof.

The object of this invention is to provide simple and highly efficient means for operating the work feed dog.

To the above end, the invention consists of the novel devices and combination of devices hereinafter described and defined in the claims.

In the accompanying drawing, which illustrates the invention, like characters indicate like parts throughout the several views.

Referring to the drawing:

Figs. 1 to 4, inclusive, are fragmentary views of a sewing machine in front elevation, with the front cover plate removed and showing different steps in the cycle of operation;

Fig. 5 is a fragmentary plan view of the sewing machine, with the top cover plate removed and showing the work feed dog mechanism positioned as shown in Fig. 1; and

Fig. 6 is a view partly in plan and partly in section taken, substantially, on the line 6—6 of Fig. 3.

The numeral 7 indicates a sewing machine casting having therein a compartment 8 provided with a top cover plate 9 and a front cover plate 10, both of which are displaceable.

Of the movable parts of the sewing machine shown, it is important to note the needle bar 11 having a needle 12, the presser foot 13, having a forwardly and upwardly inclined guide finger 14, and pivoted at 15 to a spring held bar 16, the feed dog 17 that works in and through slots 18 in the cover plate 9, only one of which is shown in Fig. 1, and the driven shaft 19 that operates the hook 20 and also the feed dog 17, as will hereinafter appear. The sewing machine parts thus far described are of standard and well-known construction.

Referring now in detail to the invention which relates to novel and highly efficient means for operating the feed dog 17. The numeral 21 indicates a carriage in the form of a flat horizontally disposed rectangular block. This carriage 21 is mounted on a pair of laterally spaced horizontal rails 22. These rails 22 are, as shown, long nut-equipped bolts, the end portions of which are mounted in the side walls of the compartment 8. The rails 22 extend through bores in the carriage 21 and support the same for free endwise sliding movement thereon. A pair of upstanding dowel pins 23 are rigidly secured to the carriage 21. These dowel pins 23 are laterally spaced longitudinally of the carriage 21.

2

A carrier 24, in the form of a block, is mounted on the dowel pins 23 that extend through bores therein and support said carrier for vertical sliding movement thereon. Extending transversely through the carrier 24, between the dowel pins 23, is a cam aperture 25 in which is mounted a cam 26 on the driven shaft 19 for operating the carrier 24. As shown, the hook 20 is integral with the face of the cam 26.

10 A bracket 27 is rigidly connected to the feed dog 17 at its rear end portion, depends therefrom and is secured to the carrier 24 by a screw 28.

It may be presumed that a cycle of operation 15 starts, as shown in Fig. 1, in which the needle 12 is in its uppermost position and the feed dog 17 is in its forward and uppermost position. The feed dog 17, when in this position, holds the presser foot 13 raised above the cover plate 9.

20 In this position of the presser foot 13 and the feed dog 17, the front end portions of said feed dog projects outwardly of the presser foot 13. When placing a piece of work, not shown, in the machine to be sewed, the same is directed by 25 the guide finger 14 onto the feed dog 17 and the initial movement of said feed dog will carry the work under the presser foot 13.

During the first step in the cycle of operation, the cam 26 moves the carrier 24 and hence the 30 connected carriage 21 and the feed dog 17 rearwardly, as shown in Fig. 2. The cam 26 positively holds the carrier 24 so that the feed dog 17 is moved in a straight line parallel to the work held on the cover plate 9 by the presser foot 13.

35 In the second step in the cycle of operation, the cam 26 moves the carrier 24 downwardly on the dowel pins 23 and withdraws the feed dog 17 from engagement with the work, as shown in Fig. 3.

40 During the third step in the cycle of operation, the carrier 24 is moved forwardly by the cam 26 with the feed dog 17 in an inoperative position in which it is moved parallel to its operative movement, as shown in Fig. 4. At this time, the 45 carrier 24 moves the carriage 21 on the rails 22.

In the fourth or last step in the cycle of operation, the cam 26 raises the carrier 24 on the dowel pins 23 and positions the feed dog 17 in its first position as shown in Fig. 1. This brings 50 the feed dog 17 again into contact with the work for feeding the same to the needle 12.

From the above description, it is evident that the feed dog 17 is moved by a single cam in a vertical plane in an endless rectangular course. 55 This movement of the feed dog 17 is highly im-

portant for the reason that the feed dog 17 is moved perpendicular to the work while being moved into engagement therewith or withdrawn therefrom. From the time the feed dog 17 engages the work until it is moved out of engagement therewith, it is moved in a straight line.

It will be understood that the invention described is capable of various modifications within the scope of the invention herein disclosed and claimed.

What I claim is:

1. In a sewing machine, in combination, guide rails, a carriage mounted on the guide rails for horizontal reciprocation, dowel pins on the carriage perpendicular to the guide rails, a carrier mounted on the dowel pins for vertical reciprocation, a feed dog on the carrier, and means for operating the carrier.

2. In a sewing machine, in combination, guide rails, a carriage mounted on the guide rails for horizontal reciprocation, dowel pins on the carriage perpendicular to the guide rails, a carrier mounted on the dowel pins for vertical reciprocation, a feed dog on the carrier, said carrier having a cam aperture, and a driven cam mounted in 25 said aperture for operating the carrier.

3. In a sewing machine, in combination, a pair of guide rails, a carriage mounted on the guide rails for longitudinal reciprocation, a pair of up-standing guides on the carriage, a carrier mounted on the guides for vertical reciprocation, a feed dog on the carrier, a transverse cam aperture in the carrier, a driven cam in the cam aperture for reciprocating the carrier, and a hook on the cam.

DAVE FISCHBEIN.
